COOLED FLAME TUBE

Peter Lloyd, Farnham, Walter Frederick Shilling,
Woking, John Brown, Highfields, and Raymond
Arthur Boulter, Great Yarmouth, England, as-
signors to Power Jets (Research and Develop-
ment) Limited, London, England, a British
company

Application July 29, 1948, Serial No. 41,277

Claims priority, application Great Britain
August 11, 1947

1 Claim. (Cl. 60—39.65)

1

This invention relates to the cooling of high temperature combustion chambers, more particularly, to cases where combustion has to be supported by an airstream of such velocity and mass flow that in order to avoid flame extinction it is necessary to screen the flame from the direct blast of the airstream and to introduce the air at successive stages in the downstream direction, thus providing a primary combustion zone and one or more further combustion and/or mixing zones.

The invention thus has particular application to cases where special problems arise due to the necessity of supporting combustion by a fast-moving airstream involving a large mass flow, as for example in gas turbine and/or jet propulsion units; the term "fast moving" is used here to indicate that the mean speed of the airstream in its general direction of flow past a combustion zone, calculated from the ratio air volume passing in unit time/cross sectional area of flow path, is substantially higher than the speed of flame propagation in the fuel/air mixture concerned. For hydrocarbon fuels burning in air the speed of flame propagation is considered as being of the order of one foot per second at atmospheric temperature; the invention, on the other hand, is especially applicable to combustion apparatus for gas turbine and/or jet propulsion power units in which the speed of the airstream in its general direction of flow past a combustion zone, calculated on the basis indicated, may be of an order as low as 10 or as high as 300 feet per second or even more, depending on the design.

In such cases combustion is generally effected in a combustion chamber or flame tube within an outer casing to which the airstream is led, fuel being injected at the upstream end of the chamber, and air being admitted from the casing into the combustion chamber at successive stages in the downstream direction. For lightness and ease of manufacture, it is advantageous for the combustion chamber to be of sheet metal, but at high temperature sheet metal walls are liable to be rapidly destroyed; moreover when low grade fuel is used there is a tendency for carbon deposition. The invention seeks to avoid both these disadvantages. The invention is also applicable to cooling the surfaces of the flow passages (including some of the blade surfaces) in high temperature gas turbines and similar rotary machines, the invention, in particular, reducing the transmission of heat to the stator and rotor, thereby permitting an increase in the working fluid temperature and thence in the efficiency.

2

With the above objects in view the invention provides a combustion chamber wherein a flow of cooling air is introduced to the radially outermost zone of the flame tube with a velocity and direction sufficiently approximating to that of the hot gas in said zone as to form an envelope of cooling air which is maintained as a separate non-turbulent flow between the hot gas and the flame tube wall for a substantial distance downstream of said zone.

In this way the flame tube wall is protected from the hot gas stream by a relatively stable insulating air layer the precise mode of introduction of which will depend on the flow distribution across the gas stream since the flow velocity past a point in the outer zone of a gas stream may or may not approximate to the mean velocity across the whole section of the stream at that point, depending on whether or not the stream is, in the region of that point, in contact with the flame tube wall which will cause the formation of a relatively stagnant boundary layer. If, for example, the point is located at the axial entry of a gas stream into a duct of much larger cross-section than the stream, the velocity in the outer zone will approximate to the mean velocity, and in this case the cooling air will be introduced with similar direction and velocity between the hot stream and the flame tube wall. On the other hand, if the point is located in the region of a stagnant boundary layer in the outer zone of the hot gas stream which is in contact over this region with the flame tube wall, the cooling air must be introduced with little or no velocity in the direction of flow, the ideal arrangement being one which employs or approximates to diffusion through a porous wall.

In order to maintain the insulating air layer over a considerable distance in the direction of the hot gas stream, it will be necessary to compensate for the loss due to mixing and temperature rise which increases with the length of the flow path; for this purpose additional cooling air is introduced to the radially outermost zone of the duct at one or more localities further downstream from the first mentioned zone to form a further envelope, and this air may be introduced in successive separate stages, or continuously in a more or less uniform manner over the required path.

Further air entries are located downstream of the annular entry and these may also be annular, or they may be radial entries adapted to prevent the formation of well defined airstreams

having any substantial penetrative power transverse to the hot gas stream.

By way of example, various forms of the invention are described below with reference to the accompanying drawings, in which:

Figure 1 is an axial section of one form;

Figure 2 is an axial section of a modification of Fig. 1.

In Figure 1, a high temperature gas duct in the form of a combustion chamber 1 of circular section is arranged co-axially within an outer air casing 2 and is provided with a hollow baffle or cap 3, having its open larger end facing downstream and forming in combination with the duct 1 an annular cooling air entry 4.

The cap 3 encloses a primary combustion zone 5 into which fuel is injected through a burner 6, and combustion is initiated by means of a spark plug 24.

The cap 3 is enclosed within a convergent tubular scoop 7 of frusto-conical form, having its upstream narrower end open to form an entry aperture 8. The wall of the chamber 1 has an upstream tubular extension 1a, enclosing said scoop 7 which defines a metering orifice and passage for the entry of primary air, while the extension 1a forms with scoop 7 a passage for a supply of cooling air through the entry 4.

The casing 2 is also provided with an extension 2a, similar to the extension 1a, and has an entry portion 2b into which is led a fast moving airstream, as for example from the compressor of a gas turbine. This airstream is divided by the extensions 1a, 2a and the scoop 7, into the three parts, of which one part forms an annular air cooling stream entering the chamber 1 through the aperture 4, a second part flows through the annular space between the casing 2 and the duct 1, while the remainder passes through the cap 3 to the primary combustion zone 5.

The dimensions of the cap 3, entry 4 and chamber 1 are such that in operation at the design point, the velocity of the air at the entry 4 and the velocity of the hot gas flowing downstream from the primary combustion zone 5 are, in the region of the aperture 4, sufficiently closely matched to enable these two streams to flow as separate streams for a substantial distance downstream of the entry 4, so as to maintain an envelope of cool air as a separate non-turbulent flow between the hot gas stream and the inner wall of the chamber 1. Since, however, the velocity of these two streams cannot be matched over a wide range of operating conditions, the velocities are preferably matched at the conditions existing at the maximum operating temperature as a breakdown of the cooling air layer at lower temperatures can be generally accepted.

The cap 3 constitutes the flame stabilising baffle generally used in such cases and is provided with an axial air entry 9 for primary air, this entry being of suitable dimensions to pass the required air flow.

The cap 3 may also be provided with swirl vanes 10 for swirling the air passing through entry 9 and circular apertures 11 and slots 12 may also be provided in the wall of the cap 3 for the entry of further primary air.

Downstream of the cap 3 are provided apertures 25 (which may also be scoops or stub pipes) in the wall of chamber 1 for the admission of further air from casing 2 to form a zone 17 where turbulence and mixing take place.

In Fig. 1 the fuel is injected downstream co-

axially into the chamber 1, but the fuel may alternatively be injected upstream, for example by suitably adapting the structure disclosed in co-pending application No. 609,532, now Patent No. 2,529,506.

It may also be possible in some cases to modify the arrangement described by dispensing entirely with a separate flame tube or inner chamber downstream of the baffle.

It is desirable to cool the chamber 1 downstream of the point at which the initial cooling air flow through the entry 4 ceases to be effective, since at high temperatures the cooling effect of the additional air normally introduced for further stages of combustion may be insufficient; moreover any turbulence so produced will promote heat exchange between the hot gases and the chamber wall, and is therefore disadvantageous. For this purpose additional flows of cooling air may be provided similar to that already described, and having at their regions of introduction into the chamber 1 a velocity comparable to that in the outermost zone of the chamber at these regions.

Such additional cooling air may be introduced through radial flow entries arranged and shaped so as to avoid the formation of well defined air-streams of substantial penetrative power transverse to the hot gas stream, thus forming over the inside of the chamber wall a relatively stable or non-turbulent insulating air layer which mixes only slowly with the hot gases due to the differing velocities and by diffusion rather than by transverse penetration.

For this purpose, as shown in Fig. 1, the wall of the chamber 1 may be provided downstream of the mixing zone with a very large number of small circular apertures 13, or by a relatively smaller number of transversely elongated apertures 14, and in either case throttling means may be provided to reduce the amount and velocity of air entering through these apertures.

In Fig. 1 throttling is effected by means of a flanged annular plate 26 suitably perforated to admit the desired air flow downstream of the plate, the whole of this admitted flow entering progressively in the downstream direction into the chamber 1.

As an alternative, the chamber 1 may be formed towards its downstream end 29 by a wall of metal gauze or of porous material, as for example, sintered metal, to permit substantially uniform entry of cooling air by diffusion from the casing 2 into the chamber 1. The chamber 1 and casing 2 are relatively tapered towards their downstream ends to provide a gradual reduction in the cross-sectional area of the annular space between them and to maintain a uniform flow of air therethrough.

As a further alternative for cooling the downstream parts of a combustion chamber use may be made of an arrangement wherein part of the airstream is first led to a locality downstream of the most upstream region at which it is required to enter the combustion chamber and is then led in the reverse direction along the outer surface of the combustion chamber to cool said surface being then allowed to enter the combustion chamber to mix with the gases of combustion.

Such an arrangement is shown in Fig. 2, which is similar to Fig. 1, except that between the casing 2 and the chamber 1 is inserted an annular shield 15, which forms, together with chamber 1, an annular space 16 open at its downstream end and closed at its upstream end.

Beyond this downstream end the casing 2 is partly closed by a stop plate 26 and an apertured flanged annular plate 26 similar to that in Fig. 1.

Air flows downstream through the casing 2, and due to the presence of the plates 26 and 28 a part of this air is reversed in direction so as to flow upstream through space 16, entering chamber 1 through entry apertures 25 to form a mixing zone 17 as in Fig. 1.

Downstream of the mixing zone, as in Fig. 1, 10 the wall of the chamber 1 may have small circular apertures 13 or transversely elongated apertures 14, and may also have a tapered outlet 29 conforming in shape to the tapered downstream end of the casing 2. Alternatively, the 15 chamber 1 may be provided at its downstream region with a wall of metal gauze or porous material as described in connection with Fig. 1.

We claim:

In combustion apparatus in which fuel is to 20 be burnt in a fast-moving airstream, and comprising an outer tubular casing having an inlet for the stream, a tubular flame tube within the casing, a hollow baffle centrally located in one end of the flame tube defining a primary combustion zone, and means for injecting fuel into said zone, said baffle being apertured to provide an inlet for part of said stream as primary combustion air to said zone, and said flame tube having an outlet at its other end, whereby the flame 30 tube defines a path for a stream of hot combustion gases; means for directing a layer of cooling air along the inside of the flame tube wall, said means comprising a tubular member enclosing the baffle and projecting for a short distance into the end of the flame tube and defining therewith an annular gap providing a path from the casing into the flame tube for a stream of cooling air,

the gap being so dimensioned in relation to the conditions inside and outside the flame tube in the conditions of operation, that the velocity of said stream of cooling air through the gap is substantially the same as the velocity of said stream of hot combustion gases.
